United States Patent [19]

Tsuchiya

[11] Patent Number: Des. 321,174

[45] Date of Patent: ** Oct. 29, 1991

[54] ELECTRONIC INSTRUMENT FOR
READING AND DISPLAYING FROM
MAGNETIC AND OPTICAL RECORDING
MEDIUMS SUCH AS FLOPPY DISKS OR
THE LIKE

[75] Inventor: Haruki Tsuchiya, Chiba, Japan

[73] Assignees: Hiuka Sangyo Kabushiki Kaisha,
Osaka; Kabushiki Kaisha System
Gijyutsu Kenkyuusho, Tokyo, both
of Japan

[**] Term: 14 Years

[21] Appl. No.: 446,407

[22] Filed: Dec. 5, 1989

CLAIM

The ornamental design for an electronic instrument for reading and displaying from magnetic and optical recording mediums such as floppy disks or the like, as shown and described.

DESCRIPTION

FIG. 1 is a top, front side perspective view of an electronic instrument for reading and displaying from magnetic and optical recording mediums such as floppy disks or the like showing my new design;

FIG. 2 is a bottom, rear, side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof.

FIG. 1

FIG. 2

FIG. 3

FIG. 4

FIG. 5

FIG. 6

FIG. 7

FIG. 8
